MEANS FOR TRIMMING LINOLEUM

Claus H. Gluesing, De Witt, Iowa

Application September 17, 1934, Serial No. 744,427

4 Claims. (Cl. 164—77)

This invention relates to means for trimming linoleum, and has for its object the provision of easily manipulated implements whereby the linoleum will be firmly supported at the point where it is to be trimmed and the cutter will be held to a rectilinear path so that the trimmed edge will be straight. The invention also has for its object the provision of a guide which will be of a sectional construction and may be easily extended to any desired length according to the width of the linoleum which is to be trimmed. It is also an object of the invention to provide means whereby the cutter will be enclosed when in use and possible injury by accidental contact with the cutter will be avoided. Other objects of the invention will appear incidentally in the course of the following description and the invention resides in certain novel features which will be particularly defined in the appended claims.

20 In the drawings:

Figure 1 is a view, partly in elevation and partly in section, of an apparatus embodying the invention.

Figure 2 is a plan view of the guide.

25 Figure 3 is an enlarged detail view of the meeting ends of two sections of the guide.

Figure 4 is an elevation of the cutter.

Figure 5 is a side view of the cutter with the protective sheath applied thereto.

30 Figure 6 is a section on the line 6—6 of Figure 5.

Figure 7 is a detail perspective view of a portion of the protective sheath.

The track consists of a series of sections, each 35 section consisting of two parallel bars 1 which may be of any suitable material and will preferably be of wood, the bars having opposed edges planed to provide a smooth straight surface and arranged with said edges close together defining 40 a slot 2 in which the cutter may operate. At each end of each section is secured a transverse block 3, the block at one end being set inwardly somewhat from the extremity thereof, as shown at 4 in Figure 3, and the block at the other end being 45 located so as to project therefrom a distance equal to the width of the space 4. Therefore, the two sections may be brought together with the projecting end of one section overlying and being supported by the projecting portion of the block 50 3 on the meeting section. The projecting block carries a stirrup or retaining band 5 which has its ends secured to the ends of said block, as clearly shown in Figure 3, and its intermediate portion spaced from the block so as to fit around the 55 meeting block, as shown in Figures 1 and 2, the

sections being thereby held in alignment and prevented from separating in a horizontal plane. One of the sections of the track is intended for use with all widths of linoleum and is intended to support a side edge portion thereof, for which purpose it is provided with the foot piece or block 6 corresponding to the blocks 3 previously mentioned but so arranged as to project slightly from the end of the section and constitute a support for a stop member 6 secured across the end of the section and having an overhanging retainer 7 secured upon its upper side. As shown in Figure 1, the retainer 7 is formed with an overhanging lip 7' in vertical spaced relation to the track members so that the edge of the linoleum, 15 indicated at 8, may be engaged under said overhanging portion and bear against the retainer so that it may be properly positioned with the slot 2 of the track at a right angle to the abutting edge of the linoleum sheet. Spurs 9 are driven 20 through the track bars 1 adjacent the retainer 7 to pierce the sheet of linoleum and thereby securely hold it in place while it is being cut.

The cutter consists of a disc 10 having its edge sharpened and disposed between two hub members or blocks 11 which serve to firmly support the disc so that it will not be apt to buckle under the strain imposed thereon. An axle 12 extends centrally through the cutter disc and the reinforcing blocks 11 and is equipped with washers 30 13 and nuts 14 against the sides of the reinforcing blocks so that when the nuts are turned home the parts will be firmly clamped together. The ends of the axles are fitted through the extremities of straps 15 which are secured to the opposite 35 sides of a handle 16 and constitute a fork for supporting the cutter when it is in use. It will now be readily understood that as many sections of the track are fitted together as may be needed to support the edge portion of the linoleum which 40 is to be trimmed and after the linoleum has been placed in proper position on the track and secured thereto, the cutter is placed upon the surface of the linoleum immediately over the slot 2 and sufficient pressure applied to the cutter to cause 45 it to pass through the linoleum. The cutter is then pushed along the track through the entire width of the linoleum and will quickly trim the same, being held to a rectilinear path by the opposed edges of the parallel track bars 1, as will be 50 understood upon reference to Figures 1 and 4.

The cutter is necessarily very keen, inasmuch as linoleum is rather tough and considerable strain is imposed upon the cutter when trimming the linoleum. If carelessly thrown aside when 55

not in use, the cutter is very apt to injure workmen or other persons who may accidentally come in contact therewith. To prevent this condition, I provide a sheath or cover for the cutter consisting of a strap 17 of leather or canvas or other flexible material provided at its ends with a buckle or similar fastening device, indicated at 18. At intervals in the length of the strap are pairs of lugs 19 which are spaced apart a sufficient distance to pass at opposite sides of the edge of the cutter and having their inner opposed faces beveled, as shown at 20, to conform to the bevel of the cutting edge. As shown in Figures 5 and 6, when this sheath is applied to the cutter, the strap will 15 pass entirely around the cutting edge and the lugs 19 will fit against the opposite faces of the cutter so as to prevent the strap slipping edgewise and will also serve to slightly space the strap from the cutting edge, as shown in Figure 5, whereby cutting 20 of the strap will be avoided. Obviously, the edge of the cutter cannot come in contact with a person when the sheath is in place. The structure of the entire apparatus is simple and inexpensive and the weight of the several elements 25 is minimized so that they may be easily manipulated without causing fatigue to the user. The reinforcing blocks 11 are circular and disposed concentric with the cutter so that they will roll upon the surface of the linoleum at the opposite 30 sides of the slot 2 and will, therefore, resist any tendency of the linoleum to buckle at its point of contact with the cutter so that the trimmed edge of the linoleum will be straight and free of any ragged or uneven portions.

35 Having thus described the invention, what is claimed as new is:

1. Means for trimming linoleum comprising a track formed in sections each section having a longitudinal slot, supporting blocks upon the under sides of the sections at the ends thereof, the

supporting block on one section being arranged to extend under the meeting end of an adjacent section to support the same, and a retaining band secured to said projecting block and engaging around the adjacent supporting block whereby to 5 hold the sections in alinement.

2. Means for trimming linoleum comprising a track having a longitudinal slot therein, an overhanging retainer at one end of the track adapted to engage over the edge of a linoleum sheet placed 10 over the track, and spurs on the track adjacent said retainer to engage and hold the linoleum sheet.

3. Means for supporting sheet material in position to be cut comprising a track formed of sections disposed in end to end relation to each other and having alined longitudinally extending slots, supporting blocks extending transversely of said sections under meeting ends thereof, the block of one section being spaced inwardly from the 20 said end thereof and the block of the other section having a portion projecting therefrom for engaging under the adjoining end of the first section and abutting the block of the first section, and a yoke carried by one block for engaging 25 about the other block and holding the sections against movement longitudinally and transversely of each other.

4. Means for supporting sheet material in position to be cut comprising a track formed of 30 sections disposed in end to end relation to each other and having alined longitudinally extending slots, supporting blocks extending transversely of said sections under meeting ends thereof, and means carried by one block for engaging about 35 the other block and detachably holding the sections in end to end engagement with each other and preventing shifting of the sections transversely of each other.

CLAUS H. GLUESING. 40
